MACHINE FOR THE MANUFACTURE OF SHEET-PAPER BLOCKS

Etienne Danger, Paris, France, assignor to
Société Anonyme Usines Découfle, Paris,
France

Application February 15, 1935, Serial No. 6,739
In France February 16, 1934

4 Claims. (Cl. 270—41)

This invention relates to machines for the manufacture of sheet paper blocks or booklets, e. g. cigarette paper blocks or booklets.

In such manufacture the purpose generally is to bring a sufficient number of continuous paper bands piled on one another all together to a cutting or assembling device whereby the same are made into blocks. Such bands frequently are wrapped in the meantime into an additional band of stronger paper to serve as a cover, folding of said cover being performed continuously e. g. by means of suitable guides whereby the marginal portions of the band are folded over the other piled up bands to form booklets.

Said bands are fed individually from as many paper reels having a large diameter as compared to their width and they run over guide rollers arranged at suitable heights in order that the bands subsequently may travel as a unitary pile 20 in a common direction up to the cutting or assembling device.

In known machines of this kind the reels are arranged side by side with their axes of rotation parallel to those of the guide rollers and consequently at right angles to the direction of travel of the band pile. The circular faces of the reels then are aligned in one plane, which results in excessive overall dimensions of the whole structure inasmuch as the space taken up by the numerous reels is considerably larger than the operative portion of the machine. Moreover, the very importance of such overall dimensions makes watching more difficult and involves the provision of automatic safety devices.

The purpose of the improvements which are the subject matter of this invention is to obviate such difficulties. Said improvements consist primarily in arranging the reels in such manner that their axes of rotation are parallel to the direction of travel of the band pile; said axes then are substantially at right angles to those of the guide rollers, so that a twist by an angle of 90° is imparted to each band on its way from the reel to the related guide roller, which twist after all involves no inconveniences. Such arrangement will allow a close grouping of all the reels in parallel relation to one another within a restricted space, whereby the overall dimensions of the machine are decreased and watching the same is facilitated. It is even possible to mount the reels on one common shaft or on parallel shafts, whereby the construction is simplified.

The invention moreover comprises a peculiar arrangement for adjusting the positions of the bands transversely so that they shall come in exact register with one another.

Figures 1 and 2 are a front and a side elevational view of a small group of reels.

Figure 3 illustrates a modification.

Figure 4 shows an adjusting device.

Figures 5 and 6 diagrammatically illustrate the entire structure of a cigarette paper block-making machine in a front and a side cross-sectional view respectively.

The reels 1, of which a considerable number may be provided, are mounted on one common or several aligned shafts XX and the paper bands 2 supplied from the reels are led while undergoing a twist at an angle of 90° to and over guide rollers 3 the shafts of which are parallel to one another and at right angles to the shafts XX. Said shafts may be arranged at the same height (Figs. 1, 2) or in stepped relation to one another (Fig. 3) depending on whether the bands are to be piled up in contact with or clear from one another.

It is necessary that the edges of the piled up bands should be aligned exactly. This result may be obtained by the use of such adjusting means as shown in Fig. 4; the shaft 4 of each guide roller then is carried by a lever 5 rockably mounted on a stationary pin 6 and subjected to the action of a spring 7 by which same is pressed against an adjustable abutment 8 arranged in a stationary support 9. By altering the position of said abutment consisting e. g. in a knurled head screw the roller can be tilted slightly upward or downward, which allows easily to adjust the position assumed automatically by the band as the same is running over said roller; in this manner transverse adjustment of the position of the band is obtained without any thrust being exerted on the edges of the latter and consequently without any danger of deterioration.

As shown in Figs. 5 and 6 the reels 1 are mounted on individual shafts 10 carried in bearings 11 secured to the frame 12 and said shafts 10 are aligned on two horizontal axes XX and X'X' above each other, the upper reels being staggered with respect to the lower ones. The paper band 2 fed from each reel runs over and between corresponding rollers 13, 14 the pins of which are mounted in the frame and arranged in parallel relation to shafts 10; the band then runs upward and over a roller 15 at the top of the machine the pin of which similarly is parallel to shafts 10 and is carried by a lever 16 mounted in the frame with provision for adjustment by means of a screw 17.

The bands 2 after they have passed over the rollers 15 are guided by rollers 18 the pins of which are mounted in the frame at right angles to shafts 10, so that they become twisted by an angle of 90° on their way from rollers 15 to rollers 18. By virtue of the adjustment of the positions of rollers 15 with respect to rollers 18 the bands will lay themselves on the latter exactly in register and will remain so without the necessity of providing said rollers with side guide jaws.

The bands as they come off from rollers 18 run over additional rollers 19, 20, the rollers 20 serv-

ing to guide or train the bands in reverse direction toward the cut off mechanism at the front of the machine between a pair of rollers 21, 22 which arrange the bands in superposed relation, 5 then between a pair of feed rollers 23, 24 which cause the bands as a whole to travel over a table 25 then through a cutting device 26 by which the unitary band pile is divided into blocks of definite length; said blocks are then taken by additional 10 rollers 27, 28 to an elevating device 29 which lifts the blocks one after the other into a magazine 30 from which they may be taken out easily. Rollers 19, 20, 21, 22, 23, 24, 27, 28 have their axes parallel to those of rollers 18, i. e. at right angles 15 to the direction of travel of the piled up bands moving toward the cutting device, which direction in the example shown is horizontal and parallel to axes XX and X'X'.

Means are diagrammatically illustrated in Figs. 20 5 and 6 to provide the piled up bands 2 with a band 31 folded into two portions and forming a band wrapper; said band is delivered from a reel 32 and runs over rollers 33, 34, 35, 36, 37 before it comes to a guide 38 by means of which it is folded 25 along its median line and to lay itself flat on the top and the bottom of the grouped bands 2.

The elevator 29, magazine 30 and wrapping device 32-38 form no part of this invention and need not be described in detail. As to the cutting device 26, this may be of any suitable construction, the cutters thereof being actuated preferably in such manner that it will involve no stopping or retardation of the band pile at the time the cutting is performed, e. g. according to a particular arrangement which provides the subject matter of a separate application.

The arrangements described above by way of non-limitating example are applicable to all machines of the kind referred to that operate either 40 with inlay sheets or with band collection or with band wrapping, etc.; they can be applied even immediately after the band-cutting and -gumming machines for the direct manufacture of blocks without the intermediate step of reeling the 45 paper.

As will be seen by referring to the drawings the several paper strips or webs 2 are fed from their reels upward over guide rollers 15, having their axes parallel with the axes of the reels. The 50 strips or webs are then fed downward and trained to travel over other guide rollers 18, 19, which cause them to move rearwardly of the machine. The strips or webs are then caused to travel about additional guide rollers 20, located at the rear of the machine and these latter rollers cause the 55 strips or webs to then travel forward toward the front of the machine and in their forward travel they pass between the assembling rollers 21 and 22, which accurately position the webs or strips in superposed relation so that from that point on the 60 superposed strips or webs travel as a unit toward the front of the machine, where they encounter the cut-off mechanism 24, which severs the traveling unit transversely into separate blocks or sections, which may or may not have covers applied thereto. When covers are to be applied the cover material is folded about the traveling unit by means of the folding guide 38, located intermediate the opposite ends of the machine.

70 By this arrangement shown and described wherein the paper webs, after leaving their reels, are first trained toward the rear of the machine and then reversed and caused to travel longitudi-

nally flatwise and in superposed relation toward the front of the machine, a very simple and compact construction is provided which greatly reduces the length of the machine since the web, assembling, the wrapper supply and the web folding mechanism as well as the web feeding rolls, 5 may all be located between the front and rear ends of the machine as viewed in Fig. 5, and wherein the feed rolls 23, 24, may be considered as being located at the front of the machine and the rolls 20 as located at the rear of the machine. Because all the mechanisms referred to are thus grouped within the overall length of the machine, such mechanisms are more convenient of access by the operator of the machine. 15

I claim:—

1. A machine of the class described, comprising a frame, a plurality of independent supports for separate reels of paper arranged to be supported at one side of the machine with their axes 20 extending in the direction of length of the machine, guide rollers for training the paper webs upward from their reels and then downwardly, said rollers being mounted on axes parallel with the axes of the reels, other guide rollers, one for 25 each web, positioned below the first named guide rollers for guiding and training the several webs of paper rearwardly of the machine, and additional guide rollers positioned near one end of the machine and about which the webs are trained 30 and by means of which they are caused to travel forward toward the front of the machine, means located in the forward path of travel of the webs for associating them in superposed relation, and means for feeding the superposed webs in a for- 35 ward direction, all of said rollers, feeding means and web associating means being located on one side of the machine.

2. A machine of the class described, comprising a frame, a plurality of independent supports at 40 one side of the machine for supporting a plurality of webs of paper with their axes extending in the direction of length of the machine, means for guiding and training the paper webs from their reels first downwardly and then rearwardly of the 45 machine, means for then training the webs forwardly toward the front end of the machine, means for assembling all of the travelling webs in superposed relation, and means for feeding the superposed webs, said feeding means being 50 located at the front of the machine.

3. A machine of the class described comprising a frame, a plurality of independent supports for separate reels of paper arranged at one side of the machine with their axes extending in the direction of the length of the machine, a plurality of levers pivotally mounted at the top of the machine, rolls mounted on the levers, the webs of paper from the reels on said supports being adapted to be fed over said rolls, adjusting means 60 for each of said rolls, other guide rolls, one for each web, arranged below said first mentioned rolls and having their axes at right angles to the first mentioned rolls for arranging the webs in a horizontal plane and in superposed relationship, 65 and a pair of feed rolls for drawing the superposed webs from said reels.

4. Apparatus in accordance with claim 3 wherein adjusting screws extend through said pivoted levers and engage a part of the frame 70 of the machine for adjusting said levers and said rolls.

ETIENNE DANGER.
